Patent expires May 2, 1965

5 Claims. (Cl. 267—1)

1

This invention relates to a resilient member having parallel terminal surfaces.

Resilient members of this kind are used if it is necessary to exert a spring pressure which, instead of being local, is divided more or less through the surface. Such is the case, for example, if the axial play must be taken out of a shaft with the aid of a resilient member. In order to avoid undesirable effects, the resultant of the forces exerted by the resilient member must be located approximately in the centre line of the shaft. To this end, it is necessary for the said forces to be somewhat divided over a circle concentric with the shaft.

A known resilient member having parallel terminal surfaces is constituted by a helical spring of which the two turns at its extremities have particular shapes. This member does not always satisfy the requirements imposed and notably it is not possible to divide the elastic forces satisfactorily with different impressions of the spring.

A further known resilient member with parallel terminal surfaces is made in the form of a spring ring substantially constituted by a plane plate furnished with radial notches. The parts located in between these notches are bent out of the surface of the plate and serve as resilient elements. In this construction it is difficult to obtain a small stiffness due to the small length of the resilient elements. Moreover, in case of overload a deformation or even fracture of one or more of the resilient elements readily occurs, resulting in a variation of the elastic properties of the spring ring.

The present invention relates to the construction of a resilient member with parallel terminal surfaces in which the drawbacks of the known construction do not occur and by which furthermore other advantages may be obtained. According to the invention, the resilient member is constituted by at least three helically wound resilient elements of same shape which are arranged coaxially but in positions which are mutually turned about the axis of the helix through angles larger than 90°, the arrangement being such that the extremities are located in two planes normal to the axis of the helix. Consequently, the resilient action is exerted in at least three points located about the axis of the helix. This remains the case with any permissible impression of the resilient member. A particular shape of the turns at the extremities is not required. By means of a symmetrical arrangement it is possible to cause the resultant of the elastic forces to fall in the axis of the helix.

2

The invention will now be explained more fully by reference to the accompanying drawing, in which,

Figure 1 shows a resilient member according to the invention, the length of which is larger than its diameter, and

Figure 2 shows a further resilient member according to the invention, the length of which is smaller than a quarter of its diameter.

10 A resilient member of the kind shown in Figure 1 is constituted by three elements 1, 2 and 3 of spring steel wire, which are helically wound in a counter clockwise manner and which are coaxially arranged so that their extremities are located in two planes normal to the axis of the helix. They are mutually turned about the axis through angles of 120°. Three helical springs 5, 6 and 7 which are clockwise wound and of somewhat smaller diameter are arranged in a 15 manner similar to springs 1, 2 and 3 and concentrically with the latter. Now, one extremity of a counterclockwise wound element is connected with an extremity of a clockwise wound element located in the same terminal surface by means of a loop located in this terminal surface. Thus, element 1 is connected with element 7 by means of a loop 8 located in the upper surface. The whole of the resilient member may 20 thus be made from one piece of spring steel wire. Upon impression due to a force exerted in the axis of the helix the upper and the bottom planes touching the three ends of the resilient elements located in the loops, remain parallel to one another.

25 The resilient member shown in Figure 2 has the shape of a spring ring and may be used to eliminate an axial play from a shaft. It is built up from three parts made from spring plate, each of which has an approximately V-shape and serves as a resilient element. The spring ring is constituted by three resilient elements 20—22 wound counter clockwise and three resilient elements 23—25 wound clockwise. Each element extends through a third of the circumference. The resilient members are assembled 30 to form one unit by one extremity of a counter clockwise wound element and one of a clockwise wound element being fixed at three points to the base. Due to the fact that the resilient elements are placed tangentially, they may be larger than in the known construction with unvaried dimensions of the spring ring. It is thus possible, if desired, to obtain a small stiffness, while overload does not readily occur. With the spring ring shown in Figure 2 all the resilient elements come 35 to lie on one another in case of overload, due

to which with still greater load there is no further deformation of the spring ring. Permanent deformation or fracture of the resilient elements is thus impossible.

The resilient member described may also be used with advantage for establishing an electric contact between parts located on each side of the member.

What I claim is:

1. A resilient member, comprising a plurality of helically wound resilient elements extending between two terminal planes perpendicular to the axis of the helix, said resilient elements being arranged coaxially in positions equally spaced about the said axis, at least three of said elements being wound clockwise and an equal number of said elements being wound counter-clockwise, each clockwise wound element in the said terminal planes being joined to a counter-clockwise wound element, the resulting joints in each terminal plane being equally distributed about the said axis.

2. A resilient member, comprising a plurality of helically wound resilient elements extending between two terminal planes perpendicular to the axis of the helix, said resilient elements being arranged coaxially in positions equally spaced about said axis, at least three of said elements being wound clockwise and an equal number of said elements being wound counter-clockwise, each clockwise wound element in the said terminal planes being joined to a counter-clockwise wound element so that each of the said elements constitutes a different portion of a continuously wound resilient member, the resulting joints in each terminal plane equally distributed about the said axis.

3. A resilient member, comprising a plurality of helically wound resilient elements extending between two terminal planes perpendicular to the axis of the helix, said resilient elements being arranged coaxially in positions spaced about the said axis, at least three of said elements being wound clockwise and an equal number of said elements being wound counter-clockwise, each clockwise wound element in the said terminal planes being joined to a counter-clockwise wound element, the resulting joints in each terminal plane being equally distributed about the said axis, each of the said resilient elements surrounding the axis of the helix over an equal angle.

4. A resilient member, comprising a plurality of helically wound resilient elements extending between two terminal planes perpendicular to the axis of the helix, said resilient elements being arranged coaxially in positions spaced about the said axis, at least three of said elements being wound clockwise and an equal number of said elements being wound counter-clockwise, each clockwise wound element in the said terminal planes being joined to a counter-clockwise wound element, the resulting joints in each terminal plane being equally distributed about the said axis, said resilient elements surrounding the said axis of the helix over an equal angle, the said resilient parts together surrounding the said axis twice.

5. A resilient member, comprising six helically wound resilient elements extending between two terminal planes perpendicular to the axis of the helix, said resilient elements being arranged coaxially in positions equally spaced about the said axis, three of said elements being wound clockwise and the other three of said elements being wound counter-clockwise, each clockwise wound element in the said terminal planes being joined to a counter-clockwise wound element, the resulting joints in each terminal plane being equally distributed about the said axis, each of the six elements surrounding the said axis of the said helix over an equal angle, the said resilient parts collectively surrounding the said axis twice, the distance between the said terminal planes being less than a quarter of the diameter of the said member.
